UNITED STATES PATENT OFFICE.

HERMAN TAPPAN, OF NEW YORK, N. Y.

DESIGN FOR A BOTTLE.

SPECIFICATION forming part of Design No. 29,125, dated August 2, 1898.

Application filed May 3, 1898. Serial No. 679,633. Term of patent 7 years.

To all whom it may concern:

Be it known that I, HERMAN TAPPAN, of the city of New York, borough of Manhattan, in the county and State of New York, have invented and produced a new and original Design for a Bottle, of which the following is a full, clear, and exact description.

Reference is to be had to the accompanying drawings, forming a part of this specification, in which—

Figure 1 is a side elevation of a bottle, showing my design; and Fig. 2 is a vertical section of the same.

The design consists of a circular base A, from which rises a cylindrical body B, slightly 15 tapering inwardly at its upper end B', terminating in a neck B², formed with raised spirals and ending in a reduced cylindrical mouth B³.

I claim—

The design for a bottle, as herein shown and described. 20

HERMAN TAPPAN.
